UNITED STATES PATENT OFFICE.

JOHN F. O'CONNOR, OF CHICAGO, ILLINOIS, ASSIGNOR, BY MESNE ASSIGNMENTS, TO
W. H. MINER, INC., A CORPORATION OF DELAWARE.

ROLLER SIDE BEARING.

Application filed January 2, 1924. Serial No. 683,905.

This invention relates to improvements in roller side bearings.

An object of this invention is to provide an efficient roller side bearing especially adapted for railway cars and wherein the anti-friction element is automatically centered when relieved of load.

More specifically, the object of my invention is to provide an anti-friction bearing adapted for attachment to a truck bolster of a railway car and wherein are employed an anti-friction roller, and pendulums so arranged that when the roller has been moved to either side of its normal central position, the pendulums will automatically return the roller to central position.

In the drawing forming a part of this specification, Figure 1 is a vertical sectional view taken through the ends of the body and truck bolsters of a car, showing my improvements in connection therewith. And Figure 2 is a vertical transverse, sectional view corresponding to the section line 2—2 of Figure 1.

In said drawing, 10 denotes the lower portion of a body bolster and 11 the upper portion of a corresponding opposed truck bolster. The improved bearing is shown applied to the truck bolster and comprises, broadly, a retaining member or housing A; an anti-friction element B; and pendulums C.

The housing or retaining member A is more or less boxlike in form, open at the top and bottom thereof, the same having opposed side walls 12 and curved end walls 13. Flanges 14 are provided at the upper ends of the sides 12, these flanges extending inwardly toward one another. Lugs or projections 15 are provided at the base of the housing for attachment to a hardened wear plate 16 interposed between the housing and the bolster. Rivets 17 or other suitable equivalent fastening means may be used for securing the heavy wear plate to the bolster. The side walls 12 are also provided with inwardly extending lugs or trunnions 18 for a purpose to be hereinafter described.

The anti-friction element B is provided with axially extending trunnions 19 at the ends thereof. As shown, the anti-friction element is adapted to roll back and forth on the wear plate 16 to either side of its normal central position, the end walls of the hous-

ing forming stops for limiting the rolling movement of the element.

In order to automatically return the anti-friction element to its normal central position when the load has been removed therefrom, I have arranged a pair of plates or pendulums C at each end of the anti-friction element B, these being individually referenced 20 and 21 for convenience of further description. The pendulum 20 is pivotally mounted intermediate its ends on the trunnion 19 while the pendulum 21 is pivotally mounted intermediate its ends on the lug or trunnion 18. The pair of members 20 and 21 are pivotally inter-connected by means of a pin 23, as shown.

From the figures shown in the drawing, it is apparent that when the anti-friction element is rolled to either side of its normal central position, as for instance when it is rolled to the left as shown in Figure 1, the pendulums 20 mounted thereon will also be swung to the left, while the pendulums 21 will be swung to the right, as the latter pendulums are pivoted at 18 to a fixed part of the housing. When the load is released, the pendulums will swing to their normal position, thus returning the anti-friction element to its normal central position. In this manner, all four pendulums assist in the return action.

In order to assemble the device, I have arranged apertures 24 through the side walls 12 of the housing, these apertures being below the normal position of the pins 23 and having their centers in the arc of travel of the pins 23. Before applying the wear plate 16, the pendulums 21 are inserted within the housing and mounted upon the lugs 18. Then the anti-friction element having its pendulums 20 mounted upon its trunnions is inserted within the housing through the bottom thereof (the housing preferably being inverted) whereupon the pendulums of each set are partially rotated until the pivot pins 23 may be driven through the apertures 24 in registry with the respective openings through the pendulums 20 and 21. After this, the wear plate may be riveted in place, thus enabling the bearing to withstand rough handling during shipment without losing any of its parts and also preventing accidental or intentional removal of the parts when in place upon the bolster.

I have herein shown and described what I now consider the preferred manner of carrying out my invention, but the same is merely illustrative and I contemplate all changes and modifications that come within the scope of the claims appended hereto.

I claim:

- 5 1. In a side bearing for railway cars, the combination with a retainer; of an anti-friction element arranged to roll to either side of normal position with respect to said retainer; means for returning said element to normal central position, including a member pivotally mounted on said element intermediate its ends, one end of said member providing a weighted portion, and means carried by said retainer and connected with the opposite end of said member, said means being constructed to develop yieldable counter-active force to the movement of said end.
- 10 2. In an anti-friction bearing, the combination with a housing adapted to be secured to a bolster; of an anti-friction element arranged to roll to either side of normal position therein; pendulums pivotally mounted on to the ends of said element; and auxiliary pendulums pivotally connected to the first mentioned pendulums and to said housing, said pendulums co-operating to return said element to normal position.
- 15 3. In an anti-friction bearing, the combination with a housing; of an anti-friction element therein adapted to roll to either side of central position; and a pair of pivotally inter-connected pendulums at each end of said element for returning it to its central position when free from load, the pendulums of each pair being swung in opposite directions when said element is actuated.
- 20 4. In an anti-friction bearing, the combination with a housing; of an anti-friction

element therein adapted to roll to either side of normal central position; and a pair of pivotally inter-connected members at the ends of said element for returning it to its central position, one of each pair of said members being pivoted to said element and the other pivoted to said housing.

5. In an anti-friction bearing, the combination with a housing adapted to be secured to a truck bolster and having inwardly extending lugs at its sides; of an anti-friction roller therein and having trunnions projecting from its ends; a pair of pivotally inter-connected pendulums at each end of said element for returning it to its normal central position when free from load, one of said pendulums of each pair being pivoted to the trunnion of said element and the other pivoted to the adjacent opposed lug of the housing.

6. In a side bearing for railway cars, the combination with a housing open at its top and bottom, having side and end walls, flanges extending inwardly across the top of said side walls, and trunnions extending inwardly from said side walls below said flanges; of a bearing plate arranged to be interposed between said housing and a bolster; an anti-friction roller adapted to roll on said plate between said side flanges and having trunnions projecting from the ends thereof beyond the edges of said flanges; and a pair of pivotally inter-connected members between the ends of said element and the opposed walls of said housing, one of each pair of members being pivotally mounted on one of said pairs of opposed trunnions.

In witness that I claim the foregoing I have hereunto subscribed my name this 29th day of December, 1923.

JOHN F. O'CONNOR.
